UNITED STATES PATENT OFFICE.

RICHARD MARMADUKE JONES, OF NORTHAMPTON, ENGLAND, ASSIGNOR TO UNITED SHOE MACHINERY CORPORATION, OF PATERSON, NEW JERSEY, A CORPORATION OF NEW JERSEY.

HEEL-ATTACHING MACHINE.

Application filed July 2, 1924. Serial No. 723,732.

This invention relates to the attachment of the heels of shoes, and is particularly concerned with the attaching, from the inside of shoes, of such relatively high and 5 heavily curved heels as those of the Louis type.

In attaching heels of this character, it has been usual, in applying pressure to retain them upon the heel-seats of the shoes 10 for nailing, to employ an abutment for the tread-surface and an abutment for the rear of the heel, as shown, for example, in United States Patent No. 1,269,654, Stan- 15 dish, June 18, 1918. Here, the rear abut- ment is mounted upon the same head that carries the tread-abutment, this arrange- 20 ment giving the necessary clearance for easy positioning of the shoe and heel and subsequent removal of the heeled shoe. While such a construction is satisfactorily 25 employed when attaching heels by short nails, which do not require heavy driving pressure, nor, consequently, great resistance to displacement of the heels, other types 30 of heels require longer attaching nails and heavier pressure to be exerted upon the tread-face, and the customary devices may not hold such heels securely. Accordingly, 35 an object of the present invention is to provide a heel-holding device, which, while giving ample clearance for the positioning and removal of the work, is adapted to retain a heel, and especially the rear portion of a heel having a considerable slope, rigidly 40 against such forces as may be exerted in driving a number of comparatively long 45 nails. This object I attain by the provi- 50 sion, in apparatus for attaching heels, of means for applying pressure to different 55 portions of such heels, as to the tread-surface and to the rear surface, the latter means being retained against rearward movement, or braced independently of its support to resist the applied pressure. The 60 pressure means preferably consist of abut- 65 ments for the tread and rear portions of the heel, which move in the operation of the machine toward and from the heel in dif- 70 ferent directions, the rear abutment being 75 movable transversely of the path of the tread-abutment. This latter movement gives 80 the desired clearance for handling the work.

The above and other objects of the in- 85 vention will become apparent from a con- 90 sideration of the following description,

given by way of example, of a construction embodying the invention and illustrated in the accompanying drawing, in which the improved abutment device, with the more closely related portions of a heel-attaching 60 machine, is shown in side elevation.

At 10 appears a part of the column or frame of such a heel-attaching machine as is disclosed in United States Patent No. 1, 285,785, Negus & Charles, Nov. 26, 1918, 65 this frame supporting a jack 12, through which the attaching nails are driven and also having mounted upon it a pressure-head 14. A pressure member or abutment 16 is carried by the head, its lower face 70 being formed and arranged to contact with the tread-surface of a heel H applied to the heel-seat of a jacked shoe S. The head may be arranged, as in the patent just cited, to be reciprocated from front to rear of the 75 machine, as well as moved vertically, the first-mentioned movement being to free the jack for the application and removal of the work, while the vertical movement places pressure upon the work, to hold the heel 80 in position during the nailing operation.

On account of the angle at which the tread-surfaces of Louis and like heels lie with relation to the heel-seats, as is well illus- 85 trated in the drawing, pressure applied by the abutment 16 results in a substantially horizontal component toward the rear of the machine, this tending to displace the heel from the shoe. This must be resisted in clamping such heels for nailing. It is 90 also desirable to hold the extreme rear portion of the heel firmly in contact with the heel-seat, to insure a tight crease when attaching nails are driven. For these purposes, there is pivoted at a point 17 upon the 95 frame fixed against movement in the operation of the machine an arm 18 having, ex- tending longitudinally, a socket to receive the shank 20 of a rear pressure-applying member or abutment 22. This abutment is 100 so curved as to approximately conform to what is normally the rear upper portion of a heel of the Louis type. The shank 20 of the abutment 22 may be adjustably clamped in place in its socket by a screw 24, which connects opposite divided portions of the wall at the under side of the socket. By 105 this means, the member 22 may be fixed in position, to best co-operate with heels of different contours. A spring 26, connect- 110

ing the arm 18 and the frame 10 or other relatively fixed point, furnishes a support for the abutment member 22, holding it normally raised in such position that it will be above and to the rear of the jack as the arm is turned about the pivot 17. This permits the application of work to the jack and its removal from said jack without interference. To move the abutment 22 into pressure-applying engagement with the rear of the heel, there is carried upon an inward extension of the abutment 16 a depending contact member 28, the extended lower surface of which is arranged to engage an upward projection from the member 22. This projection is preferably in the form of a screw 30 threaded into a boss in the abutment and held in the position to which it may be adjusted by a nut 32.

20 The shoe S having been placed upon the jack and the heel H applied to the heel-seat, the machine is started in operation, and the head 14 descends. In this movement, the contact-portion 28 first strikes the screw 30, swinging the rear abutment 22 downwardly and outwardly about its pivot 17 against the tension of the spring 26 until, when full pressure has been applied by the abutment 16 to the tread-surface of the heel, 25 the abutment 22 is in firm engagement with the rear surface, holding it closely to the heel-seat. At this time, the arm 18 is substantially horizontal, furnishing a most effective brace resisting the heel-displacing component of the pressure upon the tread. It will be seen that while the application of pressure by the rear abutment is more directly influenced by the tread-abutment, a modifying action is exercised by the connection of the arm 18 to the frame. This alters the movement of the rear abutment, causing it to travel in a path transverse to that of the tread-abutment. The proper relation between the pressure supplied by the two abutments is insured by adjustment of the screw 30, this adapting the machine to operate to the best advantage upon the particular form of heel to be attached. With this adjustment is combined that of the stem 50 20 within the arm 18 to vary the effective length of the latter, so that the desired results may be attained for heels of all curvatures and pitches. The heel having been thus clamped in place, the drivers rise in the jack to force the attaching nails through the heel-seat into the heel for its attachment. Then the head 14 is elevated, permitting the rear abutment to be lifted by its spring and swung rearwardly out of the way of the work. Since, in the form of heel-attaching machine of the patent previously referred to, the pressure-head 14 has, after the attaching operation, a rearward, as well as upward movement, there is shown between the pressure-surface of the abutment 16 and the pro-

jection 28, a recess 34, into which the screw 30 may pass as the abutment member 22 is elevated.

Having described my invention, what I claim as new and desire to secure by Letters Patent of the United States is:

1. In a heel-attaching machine, a plurality of movable pressure-applying means for contact with a heel to be attached, and means acting in the operation of the machine and arranged to cause the pressure-applying means to approach the heel from different directions.

2. In a heel-attaching machine, means for applying pressure to the tread-surface of a heel, means for applying pressure to the rear surface of a heel, a support for each pressure means, and means independent of the support for the rear pressure means for retaining said means against rearward movement.

3. In a heel-attaching machine, a frame, an abutment arranged to contact with the rear of a heel to be attached, and a brace interposed between the abutment and frame at the rear of said abutment.

4. In a heel-attaching machine, a movable tread-abutment for a heel to be attached, a movable rear abutment for said heel, means arranged to move the tread-abutment with respect to said heel, and means arranged to move the rear abutment transversely of the path of the tread-abutment.

5. In a heel-attaching machine, a plurality of movable pressure members for contact with a heel to be attached, one of said members being arranged to be influenced in its movement by another of the members, and means independent of the influencing member for modifying such movement.

6. In a heel-attaching machine, a movable tread-abutment for a heel to be attached, a movable rear abutment for the heel, connections for moving the rear abutment under the control of the tread-abutment, and other connections to the rear abutment for modifying its movement.

7. In a heel-attaching machine, a frame, a pressure member mounted to reciprocate thereon, a second pressure member movable under the influence of the associated pressure member, and pivotal connections between the frame and said second pressure member, one element of the connections being normally fixed against movement.

8. In a heel-attaching machine, a frame, a tread-abutment for a heel mounted to reciprocate upon the frame, a rear abutment for the heel oscillated by the tread-abutment, and connections between the rear abutment and the frame.

9. In a heel-attaching machine, a plurality of movable pressure members for contact with a heel to be attached, one of said members being arranged to be influenced in its

movement by another of the members, means independent of the influencing member for modifying such movement, and means arranged to vary the path of the movement.

5 10. In a heel-attaching machine, a movable tread-abutment for a heel to be attached, a movable rear abutment for the heel, the rear abutment being movable under the control of the tread-abutment, con-

10 nections to the rear abutment acting in the operation of the machine to modify the movement of the abutment, and means arranged to vary the effect of such connections.

11. In a heel-attaching machine, a frame, 15 a pressure member mounted to reciprocate thereon, a second pressure member movable under the influence of the associated pressure member, movement-modifying connections for the second pressure member made 20 to the frame at a point fixed against movement in the operation of the machine, and means arranged to vary the effective length of such connections.

12. In a heel-attaching machine, a frame, 25 a tread-abutment for a heel mounted to reciprocate upon the frame, a rear abutment for the heel movable by the tread-abutment, means arranged to vary the effect of the

tread-abutment upon the rear abutment, connections between the rear abutment and the frame, and means arranged to vary the length of the connections.

13. In a heel-attaching machine, a frame, a tread-abutment movable thereon for contact with a heel to be attached, an arm pivoted upon the frame, and a rear heel-abutment carried by the arm.

14. In a heel-attaching machine, a frame, a pressure-head movable thereon, a tread-abutment carried by the head for contact 40 with a heel to be attached, an arm pivoted upon the frame, and a rear heel-abutment carried by the arm and arranged to be moved by the head.

15. In a heel-attaching machine, a frame, 45 a pressure-head movable thereon, a tread-abutment carried by the head for contact with a heel to be attached, an arm pivoted upon the frame and having a socket, a rear heel-abutment having a shank adjustably 50 held in the socket of the arm, and a screw turning in the rear abutment and arranged for contact with the pressure-head.

In testimony whereof I have signed my name to this specification.

RICHARD MARMADUKE JONES.
